UNITED STATES PATENT OFFICE.

JULIUS B. LEVI, OF CHICAGO, ILLINOIS.

DESIGN FOR A BASE-BALL EMBLEM.

No. 38,556.

Specification for Design.

Patented May 14, 1907.

Application filed March 25, 1907. Serial No. 364,545. Term of patent 3½ years.

To all whom it may concern:

Be it known that I, JULIUS B. LEVI, a citizen of the United States, residing at Chicago, county of Cook, and State of Illinois, have invented a new, original, and ornamental Design for a Base-Ball Emblem, of which the following is a specification, reference being had to the accompanying drawing, forming a part thereof.

The figure is a plan view of the emblem showing my new design.

I claim

The ornamental design for a base ball emblem, as shown.

JULIUS B. LEVI.
